DEVICE FOR INDICATING SIGNALS ON RAILWAY VEHICLES

Filed Nov. 26, 1927

Fig. 1.

UNITED STATES PATENT OFFICE

KARL BEYERMANN, OF HAIDA, KREUZGASSE, CZECHOSLOVAKIA

DEVICE FOR INDICATING SIGNALS ON RAILWAY VEHICLES

Application filed November 26, 1927, Serial No. 235,991, and in Czechoslovakia March 2, 1926.

My invention relates to a simplified and improved device for indicating on a track-bound vehicle, particularly on the locomotive of a train, whether a line is clear or not, or whether the signal is at "clear" or at "danger". In an embodiment of my invention, a station or a line section is blocked automatically without the usual optical signals from an operator's cabin.

10 In the accompanying diagrammatic drawing:

Fig. 1 illustrates the parts on the vehicle or locomotive,

Fig. 2 shows a trackway with my improved 15 indicating device,

Fig. 3 is a plan view of the collector and the circuit breaking levers.

Referring first to Figs. 1 and 3, one embodiment of my invention will be described.

20 At one side of the track 10, Fig. 3, short current rails 11 and 12 are arranged near the distant and home signals, respectively, and insulated from the rail 10^a, are lugs or interrupter rails 13 and 14 arranged between the 25 track rails 10^a, 10^b at the same level as the rails 11, 12, the object of the interrupter rails being described below.

15 is a line connecting the rails 11 and 12 through a resistance 16 and a wire 17, with 30 a contact 18, 19 being another contact, and 20 being a contact lever adapted to cooperate with 18 and 19 and to be controlled from the operator's cabin, not shown. 21 is a battery which is connected at one terminal with the 35 manually controlled contact lever 20, and earthed across the rails 10^a, 10^b at the other terminal as shown at 22.

Referring now to Fig. 1, 23 is a collector supported on the frame of the locomotive or 40 the like between two of its wheels, and 24, 25 and 26 are its contact levers which are insulated from the locomotive and permanently slide on the rails 10^a during the down-journey and on the rails 10^b during 45 the up journey. They slide also on the current rails 11, 12, the distance between the several contact levers being a function of the length of the rails 11, 12. The distance between two contact levers is somewhat 50 smaller than the length of a current rail,

and may be about 19 3/4 in., so that in the case of three contact levers the total duration of contact corresponds to a distance of about 4 ft. 11 in. which at a speed of 75 m. p. h., gives a contact period of about 1/20 second. 55 For locomotives of larger wheelbase, as express locomotives, the contact period may be extended by increasing the number of contact levers in the collector 23. On single-track lines where the locomotives must be turned about, and current rails are provided on one side of the track only, obviously the locomotives must be equipped with two collectors.

27, 28 are circuit breaking levers on the locomotive, 29, 30 are a first, 31, 32 a second, and 33, 34 a third pair of switches the movable contacts of which are carried by one or the other of the circuit breaking levers 27, 28. The switches 29, 30 and 31, 32 are 60 normally closed, while the switches 33 and 34 are normally open. The interrupter rail 14 is so wide as to cooperate with both levers 27, 28, and the interrupter rail 13 is only so wide that only a single circuit breaking lever 65 cooperates with it, this being the lever 27 for forward, and the lever 28 for reverse running. For single tracks, the circuit breaking levers are adapted to be displaced laterally in order to prevent interference when a 70 signal is in the "danger" position but the locomotive is running against it. As shown in Fig. 4, a rack 35 is provided in cooperation with a bell-crank lever 36 for moving the circuit breaking levers 27, 28 into the dotted- 75 lines position.

37 and 38 are electromagnets adapted to operate an optical signal 37^a and 38^a on the locomotive, and 39 is a battery which normally excites the electromagnets, the magnet 37 80 indicating (when deenergized) "stop", 38 indicating (when deenergized) "caution".

Assume that the distant and home signals at 11 and 12 are in the "clear" position and a train is approaching from the left in Fig. 95 3, the switching lever 20 is on contact 18, connecting the lines 15, 17 and consequently the rails 11, 12, to the battery 21. When the locomotive runs past the distant signal at 11, the lever 27 is operated by the interrupter 100

rail 13, opening the switches 30 and 32, but closing the third switch 34, and the collector 23 will close two circuits, viz.: I. from battery 21 past 20, 18, 17, 16, 15, 11, 23, 40, 41, 34, 42, 43, 38, 44, 45, and to earth at 22 through the wheels and the track, and II. from battery 21 past 20, 18, 17, 16, 15, 11, 23, 40, 47, 48, 37, 44, 45, and to earth at 22, keeping the magnets 37, 38 excited. At the home signal near the rail 12, both circuit breaking levers will be operated by the rail 14, and the connections described will again be made, but in addition the first and second switches 29, 31 will be opened and the third switch 33 will be closed. Thus, in addition to the circuits I and II, (in which obviously "11" must be replaced by —12—), a circuit III. is established as follows: Battery 21, 20, 18, 17, 16, 15, 12, 23, 40, 41, 33, 49, 42, 43, 38, 44, 45, and to earth at 22. The line 45 is connected, in a manner not shown, to the metal masses of the locomotive, which by means of the contact between the wheels and the rails are in connection with the earth at 22. In this case as well, both magnets 37, 38 will remain excited. Consequently, as no alteration occurs in the signalling apparatus on the locomotive, the driver notices that the line is clear. When the signals are at "danger" the switching lever 20 is thrown over to the contact 19, disconnecting the two rails 11 and 12 from the battery 21. When the locomotive runs past the interrupter rail 11 the lever 27 will be operated and the third switch 34 will be closed but the circuit I, as mentioned, is broken at 18. By opening the switches 30 and 32 the local circuit "IV" of the electromagnet 38 has been opened which is as follows: 39, 50, 29, 51, 30, 42, 43, 38, 44, 45, 39. The local circuit "V" of the electromagnet 37, viz. 39, 50, 31, 47, 48, 37, 44, 45, 39, remains closed. The deenergized signalling electromagnet 38 operates a signal, not shown, indicating "danger". Only when the broad interrupter rail 14 is reached, that is, when both circuit breaking levers 27, 28 are raised, the local circuit "V" on the locomotive is interrupted besides the local circuit "IV" as in this case the two switches 29 and 31 are opened as well.

Both signalling electromagnets become deenergized and the electromagnet 37 influences the signalling device with which it is connected so that a "stop" signal will be given on the locomotive.

I claim:

1. In a device for indicating signals on track-bound vehicles two signalling current rails arranged in succession and adapted to be disconnected from a source of current when the signal is at "danger", two lugs, each co-ordinated to one of said rails, a collector on said vehicle adapted to move permanently on one of the rails of said track and adapted to cooperate with the said rails, two circuit

breaking levers adapted to be operated independently of each other, one of said lugs being adapted to operate but a single circuit breaking lever, the other being adapted to operate both levers, two electromagnets, each electromagnet having in its circuit a first and a second switch, a movable contact of one of said first switches being permanently engaged with the fixed contact of the other first switch, and a permanent conductive connection between the movable and the fixed contact parts of the two second switches, each circuit breaking lever supporting the movable contacts of one each of said first and second switches.

2. In a device according to claim 1 having a permanent conductive connection between said collector and the movable contact parts of the two second switches, two third switches, the movable contacts of said third switches being arranged on one of said circuit breaking levers, a permanent conductive connection between said contacts and the lever on which they are supported, the fixed contacts of said third switches being permanently connected with said movable contact part of one of said first switches, and said circuit breaking levers being adapted to open the said first and second switches, and to close the third switches, and vice versa, when operated by said circuit breaking levers.

In testimony whereof I have hereunto affixed my signature.

KARL BEYERMANN.
